CONTINUOUS MINER FOR PITCHING SEAMS
HAVING AN ANGULARLY ADJUSTABLE
TRIMMER BAR

Emil J. Hlinsky, La Grange Park, Ill., assignor to Goodman Manufacturing Company, Chicago, Ill., a corporation of Illinois

Application January 22, 1958, Serial No. 710,536

5 Claims. (Cl. 262—7)

This invention relates to improvements in mining machines of the boring type and more particularly relates to such machines adapted for operation in pitching seams of coal.

A principal object of the present invention is to provide a continuous mining machine of the boring type having improved support means for the upper trimmer bar accommodating the upper trimmer bar to cut at the angle of pitch of a pitching seam of coal while the machine operates along the level.

A further object of the invention is to provide a continuous mining machine of the boring type in which the upper trimmer bar is vertically adjustable, and is also tiltable to conform to the angle of pitch of a pitching seam or coal.

Another object of the invention is to provide a continuous mining machine particularly adapted for cutting in pitching seams of coal having an upper trimmer bar supported for vertical adjustment on fluid operated jacks, and wherein the jacks are connected to the upper trimmer bar by pivotal connections, one of which accommodates angular movement of the trimmer bar about the other of said pivotal connections and relieves binding from the jacks during operation thereof.

A still further object of the invention is to provide a continuous mining machine of the boring type in which the cusps between the boring heads are cut out by cutter chain carrying trimmer bars, in which the upper trimmer bar is vertically and angularly adjustable with respect to the body of the machine, to conform to the angle of pitch of the pitching seam, and in which simplified connections are provided between the adjusting means and the trimmer bar, accommodating free angular movement of the trimmer bar about either of the adjusting means.

These and other objects of the invention will appear from time to time as the following specification proceeds and with reference to the accompanying drawings wherein:

Figure 1 is a view in front elevation of a continuous mining machine constructed in accordance with the invention;

Figure 2 is an enlarged fragmentary view in front elevation, showing the adjustable mounting for the upper trimmer bar on the gear box for the machine, with certain parts broken away and shown in section, in order to illustrate certain details of the invention;

Figure 3 is an enlarged fragmentary sectional view taken substantially along line 3—3 of Figure 2;

Figure 4 is an enlarged fragmentary sectional view taken substantially along line 4—4 of Figure 2; and

Figure 5 is a diagrammatic front end view of the machine, illustrating the operation of the machine in a pitching seam of coal.

In the embodiment of the invention illustrated in the drawings, 10 generally designates a mining machine of the boring type having a transversely extending frame in the front of a gear case 11, supported in advance of

2

the main frame of the machine (not shown) for vertical adjustment with respect to the ground. The gear case 11 has a central throat 12, providing a passageway to an inclined elevating conveyor 13, for picking up the mined material and transporting it beyond the rear end of the machine for loading into shuttle cars (not shown) and the like.

The gear case 11 has spaced hubs 15 projecting forwardly therefrom, on opposite sides of the throat 12 and the elevating conveyor 13, and forming bearing supports for spaced rotatable boring heads 16. The boring heads 16 are positioned to cut in intersecting paths out of phase relation with respect to each other, as diagrammatically illustrated in Figure 5. Each boring head 16 is shown in Figure 1 as including boring cutters 17 spaced radially from the center of the hub 15, in diametrically opposed relation with respect to each other, and boring cutters 19 and 20 on the outer ends of arms 21, extending between the cutters 17 in diametrically opposed relation with respect to each other. The boring heads 16 may be of various forms well known to those skilled in the art, and are no part of the present invention so need not herein be shown or described further.

A lower transversely extending trimmer bar 22 is suitably mounted on the gear case 11 behind the boring heads 16. The trimmer bar 22 serves as a guide for a cutter chain 23, guiding said cutter chain to cut along the mine bottom tangentially to the cutting paths of the boring heads 16. Corner sprockets 24 serve as direction changing devices about which the cutter chain 23 changes its direction of travel at opposite ends of the trimmer bar 22. The corner sprockets 24 may be mounted for retractile movement with respect to the trimmer bar 22, to accommodate retraction of said corner sprockets 35 when it is desired to move the machine from working place to working place in the manner upper sprockets 25 are retractile mounted on an upper trimmer bar 27, as will now be described.

The upper trimmer bar 27 extends between the boring heads 16 and is positioned to guide the cutter chain 23 to cut tangentially to the cutting paths of said boring heads when in the horizontal cutting position shown in Figure 1, for cutting out the depending cusps of unmined coal left between the boring heads 16.

The upper trimmer bar 27 is mounted on the gear case 11 for vertical and angular adjustment relative thereto by means of laterally spaced hydraulic jacks 29. The jacks 29 include cylinders 30, shown as being mounted on the forward face of the gear casing 11 and extending vertically therealong in parallel spaced relation with respect to each other. Piston rods 31 are extensibly movable with respect to the cylinders 30, upon the admission of hydraulic fluid under pressure to the head ends of said cylinders and are pivotally connected with the trimmer bar 27 for supporting and vertically and angularly moving said cutter bar, in a manner which will hereinafter be more clearly described as this specification proceeds.

The corner sprockets 25 are mounted on lever arms 33, to normally be spaced beyond opposite ends of the trimmer bar 27. Said lever arms 33 are pivotally mounted on said trimmer bar adjacent the ends thereof, on transverse pivot shafts 35, carried in depending support portions 36 depending from said trimmer bar.

The corner sprockets 25 are maintained in extended relation with respect to the trimmer bar 27 by fluid pressure cylinders 37. Pivot pins 39 are provided to pivotally connect the head ends of said cylinders to ears 40 depending from the trimmer bar 27 inwardly of the ends thereof.

Piston rods 41 extensible from the cylinders 37 are pivotally connected to arms 43 of latching levers 44,

Pivot pins 45 pivotally mount the latching levers 44 on depending supports 46, depending from the trimmer bar 27, adjacent opposite ends thereof. The latching levers 44 have upwardly extending latching arms 47 having dogging abutments 48 on the upper ends thereof, engageable with lugs 49 depending from the arms 33 intermediate the ends thereof. The dogging abutments 48 form stops for the lugs 49, for retaining the arms 33 in extended relation with respect to the trimmer bar 27 as fluid is held within the cylinders 37.

The corner sprockets 25 are retractably moved with respect to the ends of the trimmer bar 27 upon the admission of fluid under pressure to the head ends of the cylinders 37, by operation of connecting links 50. Each connecting link 50 is pivotally connected to an arm 33, intermediate the ends thereof, on a pivot pin 51 and is pivotally connected to the dogging arm 47, intermediate the ends thereof, on a pivot pin 52. Thus, as fluid under pressure is admitted to the head ends of the cylinders 37, the latching levers 44 will be pivoted in an inward direction to effect movement of the dogging abutments 48 in a direction away from the lugs 49 and to accommodate retractable movement of the arms 33 and corner sprockets 25 through the connecting links 51 connected to the arms 33. In a contrary manner, upon the admission of fluid under pressure to the piston rod ends of the cylinders 37, the links 50 will move the latching levers 47 in an outward direction, to extensibly move the arms 33 and corner sprockets 25 until the dogging abutments 48 come into engagement with the lugs 49, to positively hold the arms 33 and corner sprockets 25 in the extended positions shown in Figure 2.

The cutter chain 23 is trained beyond the ends of the upper cutter bar 27 around the corner sprockets 25, and angularly inwardly and downwardly therefrom. One run of the chain is trained around a drive sprocket 53 mounted on the gear casing 11 and suitably driven from the gearing which drives the boring heads 16. The other run of the chain is trained around a tension idler 54. The cutter chain is then trained angularly outwardly and downwardly from the sprockets 53 and 54 to and around the opposite corner sprocket 24 and along the lower trimmer bar 22.

The tension idler 54 is shown as being mounted on a shaft 79 carried by a take-up indicated generally by reference character 80. Said take-up is provided to take-up or release tension from the cutter chain 23 in accordance with the position of the cutter bar 27 with respect to the gear housing 11, and may be of any well known form, and is no part of the present invention, so need not herein be shown or described further.

Referring now in particular to the support for the trimmer bar 27 on the jacks 29, accommodating tilting movement of said trimmer bar to conform to the angle of pitch of a pitching seam of coal, the trimmer bar 27 is provided with spaced slots 55 extending vertically therethrough, for receiving enlarged connecting end portions 56 of the piston rods 31. As shown in Figures 2 and 3, the left hand piston rod 31 and connecting end portion 56 is mounted on a pivot member 57. The pivot member 57 has reduced diameter shaft portions 59 extending from opposite sides thereof concentric with the center thereof, one of which shaft portions is shown in Figure 3 as being mounted in the trimmer bar 27 on a bearing 60. The opposite shaft portion 59 is shown as being rotatably mounted within an end cap member 61, extending within an opening 63 affording access to the slot 55, and retained to said trimmer bar as by cap screws 65.

The right hand piston rod 31 and enlarged diameter connecting end portion 56 thereof is shown as being mounted on a pivot member 67 having shaft portions 69 extending from opposite ends thereof, eccentric of the center of said pivot member. The inner shaft portion 69 is shown in Figure 4 as being rotatably mounted in

a bearing 70, mounted in the cutter bar 27. The opposite shaft portion 69 is shown as being rotatably mounted within an end cap 71, mounted within an opening 73 affording access to the slot 55, and secured to said cutter bar 27, as by cap screws 75.

Thus, upon the admission of pressure to either of the cylinders 30, to angularly position the cutter bar 27 with respect to the gear casing 11 about the center of connection of either jack to the cutter bar 27, the pivot member 67 will pivot about the shaft portion 69 thereof, to conform the spacing between the centers of connection of said jacks to said cutter bar to an arc struck from the center of the pivot about which said cutter bar moves, to compensate for the increasing or decreasing distances between the centers of the bearing members 57 and 67, due to angular movement of the cutter bar about a fixed pivot, and to thereby relieve the fluid pressure jacks 29 from lateral binding pressures thereon.

In operation of the machine to cut and load a pitching seam, as shown in Figure 5, the lower trimmer bar 22 and machine frame are level with respect to the seam, the lower trimmer bar trimming the floor to extend horizontally. The upper trimmer bar 27 is shown as being angularly adjusted to the angle of pitch of the seam. This may be attained by the admission of fluid under pressure to one cylinder 29, depending upon the direction of the pitch under the operation and control of the conventional valves. When the upper trimmer bar has been adjusted to the proper angle, fluid under pressure may then be held in both ends of the two cylinders 30, to hold the upper trimmer bar 27 to position the cutter chain 23 to cut at the angle of pitch of the coal seam along the mine roof, tangentially to the path of cutting of one boring head 29 and trimming the depending cusps left between the boring heads, as well as trimming the area above the opposite boring head 29, to provide a clean roof for substantially the entire width of the machine.

While I have herein shown and described one form in which my invention may be embodied, it will be understood that various modifications and variations thereof may be effected without departing from the spirit and scope of the novel concepts of the invention, as defined by the claims appended hereto.

I claim as my invention:

1. In a mining machine of the boring type particularly adapted for operation in pitching seams of coal and the like, a mobile frame, a pair of laterally spaced boring heads rotatably mounted on said frame for cutting contiguous bores in advance of said frame, a horizontally disposed cutter chain carrying trimmer bar for cutting a kerf generally tangentially to the path of cutting of at least one of said boring heads, extensible fluid pressure jacks for vertically and angularly adjusting said trimmer bar relatively to said boring heads, individual connecting means for each jack, pivotally connecting said jacks with said trimmer bar and mounting said trimmer bar for angular adjustment about either of said connecting means, one of said connecting means accommodating angular movement of said trimmer bar about one of said jacks and moving the center of connection of said one jack to said trimmer bar to conform to an arc struck from the axis of angular adjustment of said trimmer bar and thereby compensating for the variations in spacing between the axes of connection of said jacks to said trimmer bar upon angular movement of said trimmer bar.

2. In a mining machine of the boring type particularly adapted for mining pitching seams of coal and the like, a mobile frame, a pair of laterally spaced boring heads rotatably mounted on said frame for cutting contiguous bores in advance of the machine, a horizontally disposed cutter chain carrying trimmer bar mounted on said frame for making a trimming cut along the mine roof generally tangentially to the path of cutting of at least one of said boring heads, independently operable extensible fluid

pressure jacks for adjusting said trimmer bar relatively to said boring heads, pivot members connecting said jacks to said trimmer bar, one of said pivot members connecting an associated jack to said trimmer bar and mounting said trimmer bar for angular movement about an axis concentric of the center of said pivot member and the other of said pivot members connecting an associated jack to said trimmer bar and mounting said trimmer bar for angular movement about an axis displaced from the center of said pivot member and compensating for angularity of movement of said trimmer bar with respect to said jacks, upon operation of either of said jacks.

3. In a mining machine of the boring type particularly adapted for mining pitching seams of coal and the like, a mobile frame, a pair of laterally spaced boring heads rotatably mounted on said frame for cutting contiguous bores in advance of said frame, a transversely extending cutter chain carrying trimmer bar mounted on said frame for cutting generally tangentially to the extreme upper limits of the path of cutting of at least one of said boring heads, support means for said trimmer bar on said frame comprising independently operable extensible fluid pressure jacks, pivotal connections between said jacks and said trimmer bar, at least one of said pivotal connections comprising a rotatable pivot member connecting an associated jack to said trimmer bar and being mounted for rotation about an axis eccentric of its center to compensate for the variations in distance between points concentric of said pivot members upon angular movement of said trimmer bar about the pivotal connection of one of said jacks with said trimmer bar.

4. In a mining machine of the boring type particularly adapted for mining in pitching seams of coal and the like, a mobile frame, a pair of laterally spaced boring heads rotatably mounted on said frame for cutting contiguous bores in advance of the machine, a horizontally disposed cutter chain carrying trimmer bar for cutting generally

tangentially to the uppermost limits of the path of cutting of at least one of said boring heads, means for supporting said trimmer bar on said frame comprising extensible fluid pressure jacks independently operable to move vertically and angularly move said trimmer bar with respect to said frame, pivotal connections between said jacks and said trimmer bar comprising rotatable pivot members connecting said jacks to said trimmer bar, one of said pivot members being rotatable about an axis concentric with its center and the other of said pivot members being rotatable about an axis eccentric of its center to accommodate angular movement of said trimmer bar about said pivot members without binding between said trimmer bar and jacks.

15 5. In a mining machine of the boring type particularly adapted for pitching seams of coal and the like, a mobile frame, a pair of laterally spaced boring heads rotatably mounted on said frame for cutting contiguous bores in advance of the machine, a horizontally disposed lower trimmer bar mounted on said frame for cutting the upstanding cusp left between said boring heads, an angularly movable upper trimmer bar adjustably mounted on said frame for cutting at the angle of pitch of the pitching seam along the mine roof, means supporting said upper trimmer bar on said frame and vertically and angularly adjusting said trimmer bar with respect to said frame comprising laterally spaced fluid pressure jacks operable independently of each other having cylinders rigidly mounted on said frame and piston rods extensible therefrom, spaced pivot members mounted on said trimmer bar and forming pivotal connections between said piston rods and said trimmer bar, at least one of said pivot members being rotatable relative to said trimmer bar and piston rod about an axis eccentric of its center.
